US00D791217S

(12) **United States Design Patent** (10) **Patent No.:** **US D791,217 S**
Wang (45) **Date of Patent:** **** Jul. 4, 2017**

(54) **CARRIER WITH IMAGE CAPTURING DEVICE**

(71) Applicant: **SZ DJI Technology Co., Ltd.**, Shenzhen (CN)

(72) Inventor: **Zhen Wang**, Shenzhen (CN)

(73) Assignee: **SZI DJI Osmo Technology Co., Ltd.**, Shenzhen (CN)

(**) Term: **15 Years**

(21) Appl. No.: **29/556,328**

(22) Filed: **Feb. 29, 2016**

FIG. 1 is a top front perspective view of a carrier with image capturing device showing the claimed design;
FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the carrier with image capturing device and environment that form no part of the claimed design.

1 Claim, 7 Drawing Sheets
